UNITED STATES PATENT OFFICE.

GEORGES POURÉ, OF BOULOGNE-SUR-MER, FRANCE.

WINDING-REEL.

No. 810,977.

Specification of Letters Patent.

Patented Jan. 30, 1906.

Application filed October 18, 1902. Serial No. 127,155.

To all whom it may concern:

Be it known that I, GEORGES POURÉ, a citizen of the Republic of France, and a resident of Boulogne-sur-Mer, France, (whose postal address is Boulogne-sur-Mer, Pas-de-Calais, France,) have invented certain new and useful Improvements in Winding-Reels, of which the following is a full and complete specification, such as will enable those skilled in the art to which it appertains to make and use the same.

The subject of my invention is winding-reels used for spinning and stocking frames and the like.

15 The shaft or axis of winding-reels has hitherto been made of wood in which the pointed ends of the iron-wire arms are driven in radially. I now make such winding-reels entirely of metal for the purpose of a greater strength 20 and much longer use of the reel.

In the accompanying drawings, Figure 1 is an elevation of a winding-reel. Fig. 2 is a plan of the same. Fig. 3 shows a modified construction, a part being removed. Fig. 4 25 represents, on an enlarged scale, a perspective view of an end disk of the reel. Fig. 5 is a section of said disk. Fig. 6 shows, on an enlarged scale, a plan of a part of a central disk with passages *b b'* and with a radial arm 30 in place and fixed by squeezing. Fig. 7 is a section on line 7 7 of Fig. 6. Fig. 8 is a section on line 8 8 of Fig. 6.

Hitherto the shaft of a winding-reel has been made of a piece of wood cylindrical in 35 the middle and strengthened at the two ends in order to form the necessary thickness in which the pointed ends of the radial iron-wire arms are embodied. In drying, the wood often cracks, and even without that the 40 arms easily come out. In order to obviate these disadvantages, I make reels entirely of metal, and consequently much more durable, the radial arms of which cannot be pulled out except with considerable force.

45 In the form illustrated in Figs. 1 and 2 the shaft or spindle consists of a metal rod *A*, the two ends *a a* of which pass through the holes formed in the center of the two rings *B*, these ends forming the pins around which the reel

rotates. The only difference in the two 50 forms of construction is in the shaft or spindle and its attachment to the apparatus. The rings and the radial arms are the same.

In the form of construction illustrated in Fig. 3 the "sleeve" is formed by a tube *A'*— 55 that is to say, this tube is intended to be placed on the spindle around which the reel rotates. Toward each of the two ends this sleeve is furnished with two shoulders *a' a'*. Against each of these shoulders two stamped 60 rings *B B* rest, which are held on the outside by settings or shoulders formed by the ends of the tube *A'*. Thus the rings are held in recesses formed by the inner and outer shoulders. The rings *B B*, which might be perforated 65 in order to lighten them, are furnished, for example, with passages *b b*, corresponding in number with the radial arms *C*, to be introduced therein. The bend of the radial arms may vary, as shown. When the radial 70 arms are in their places, having passed through the passages *b b*, pressure is applied to the whole, and the ends of the radial arms are thus firmly incased in the rings.

Figs. 6, 7, and 8 show how the arms *C* are 75 held in the passages after this pressure has been applied. The pressure slightly bends and flattens the arms *C* and enlarges those portions which are exposed between the passages *b b*, and thus the arms are rigidly held. 80

Having now described my invention, what I claim as new, and desire to secure by Letters Patent, is—

A metallic reel consisting of an axle, a disk of sheet metal on each end thereof, each of 85 said disks having hollow stamped ribs projecting alternately on both sides thereof forming radial passages, metallic rods having their ends placed in the passages and held therein by squeezing the ribs on both sides of the disk 90 against the rods so as to slightly bend and flatten said rods, substantially as described.

In witness whereof I have hereunto set my hand in presence of two witnesses.

GEORGES POURÉ.
